Inventor:

Louis C. Rodier.

Thos. J. Sprague

UNITED STATES PATENT OFFICE.

LOUIS C. RODIER, OF DETROIT, MICHIGAN.

RADIATOR.

SPECIFICATION forming part of Letters Patent No. 292,362, dated January 22, 1884.

Application filed October 1, 1883. (No model.)

To all whom it may concern:

Be it known that I, LOUIS C. RODIER, of Detroit, in the county of Wayne and State of Michigan, have invented new and useful Improvements in Radiators; and I do hereby declare that the following is a full, clear, and exact description thereof, reference being had to the accompanying drawings, which form a part of this specification.

10 This invention relates to certain new and useful improvements in the construction of radiators of that class designed for use in heating by the circulation of hot water, and is especially designed as an improvement upon the Letters Patent granted to me March 3, 1881.

The invention consists in the peculiar construction, arrangement, and various combinations of the parts, all as more fully herein-20 after set forth.

Figure 1 is a plan of one section of a return-coil partially broken away at the hub. Fig. 2 is a cross-section on the line xx , Fig. 1. Fig. 3 is an elevation of a stack or nest 25 of my radiators, with the top coil in section.

In the accompanying drawings, which form a part of this specification, A represents a single radiator-coil, which is provided with a hollow hub a at or about its longitudinal center. Within this hub I rigidly secure the diaphragm B, which divides the hub and one leg of the radiator into two compartments, as is clearly shown in the drawings. When but one coil is employed, it is connected at the hub, upon opposite sides of the diaphragm, by suitable pipes leading to the boiler. The water enters through the hub and strikes upon the top of the diaphragm, by which it is deflected into the radiator and compelled to 30 travel entirely around through both legs thereof and discharge through the hub beneath the diaphragm. When a nest of these radiators is used, the hubs of the series are connected together by nipples C, the upper and lower 35 members of the series being connected to the supply and discharge pipes, and the whole mounted upon any suitable base. In short radiators, owing to the hubs being in their

longitudinal and transverse centers, they will be sufficiently supported by their hubs; but in 50 stacks, where they are of any considerable length, their ends should be supported by proper steady-blocks, D.

A radiator may be constructed of any desired size, singly or in nests, and water be circulated continuously through any number, the water being compelled to flow successively from one to another throughout the entire series.

I am aware of Patents Nos. 176,056 and 60 265,279, and make no claim to the construction shown therein, as I deem my invention essentially different therefrom, and believe that it possesses decided advantages over the devices shown in said patents. By constructing a radiator of the form shown, and providing the same with a hollow hub at its longitudinal and transverse center, instead of at one end, the same can and will be supported by the hub independent of other supports, 65 70 although when the coils are very large supports may be used at the ends, as shown in the drawings, so that when arranged in stacks the hubs prevent the coils from sagging and serve to keep them level, thus insuring a certain and continuous flow of water through the 75 entire series.

What I claim as my invention is—

1. A hollow link-shaped radiator, A, having a hollow hub at its longitudinal and transverse center, within which and one leg of the radiator is placed a diaphragm, dividing them into two compartments, substantially as described.

2. Two or more radiators, A, having hollow hubs at their longitudinal and transverse centers, constructed substantially as described, each of which is provided with a central hub and a diaphragm, and adapted to be secured together by a nipple, C, entirely inclosed by 85 90 said hubs, substantially as specified.

LOUIS C. RODIER.
